SLUG EJECTING MECHANISM FOR TYPOGRAPHICAL SLUG CASTING MACHINES

Christian Augustus Albrecht, Berlin, and Paul Skrabel, Berlin-Lubars, Germany, assignors to Mergenthaler Linotype Company, Brooklyn, N. Y., a company of New York

Application October 22, 1938, Serial No. 236,464
In Germany February 25, 1938

12 Claims. (Cl. 199—60)

This invention relates to typographical slug casting machines, such as those known under the registered trade-mark "Linotype", and is directed to the slug ejecting mechanism used therein.

5 In known slug casting machines, the slugs cast in the moulds are ejected by ejector blades, and it has already been proposed to replace a solid ejector blade by a composite plate made up of a number of narrow strips or blades and to 10 couple the required number with the operating mechanism so as to ensure that the ejector in use for the time being will be appropriate to the length of the slot of the mould actually in use. In the case of the machines heretofore proposed 15 having such an arrangement, it is necessary each time a mould is adjusted to a different slot length also correspondingly to adjust the ejector blades, that is to couple with the operating mechanism, by hand, a greater or smaller number of the 20 sectional plates.

The present invention is intended to eliminate the work connected therewith and the loss of time incurred, more especially when frequent mould changes have to be made, and this by 25 effecting automatically the adjustment of the ejector blade width.

With this end in view the invention consists in slug ejector mechanism for a typographical slug casting machine comprising an ejector blade 30 formed from a plurality of adjustable elements, a greater or less number of which can be used together in order to form a blade of width corresponding to the length of the mould slot in use, and means for advancing the elements to the 35 mould and mould slot prior to a casting, thereby automatically selecting for setting, and thereafter locking in operative positions, the number of elements appropriate to the mould slot in use, while retaining the remaining elements in 40 operative positions. Thus when employing the invention it is merely necessary to bring a fresh mould with a longer or shorter slot length into the operative position in the regular manner, and the ejector blade width required is adjusted 45 automatically.

The invention will be clearly understood from the following description of one form which it may assume, and this description will be more readily followed by reference to the accompanying drawings which illustrate by way of example one constructional form of the invention, and in which:

Figure 1 is a side elevation of the ejecting mechanism and of adjacent machine parts in

their initial positions in mechanism according to the invention;

Figure 2 is a similar view but shews the parts after the adjustment of the ejector blade width has taken place; 5

Figure 3 is an illustration of the same parts when the ejection of the slug from the mould is taking place;

Figure 4 is a horizontal section through Figure 1 taken on the line 4—4; 10

Figure 5 is a section through Figure 2 taken on the line 5—5;

Figure 6 is a section through Figure 2 taken on the line 7—7;

Figures 7 and 8 are sections through Figure 3 15 taken on the lines 7—7 and 8—8 respectively;

Figure 9 is a combined view of part of the section according to Figures 5 and 6 drawn to a larger scale;

Figures 10 and 11 represent respectively in 20 side and front elevation the essential parts of a modified form of the invention; and

Figure 12 represents in plan, on an enlarged scale, a detail shown in Figure 10.

In carrying the invention into effect in one 25 convenient manner as shown in Figures 1 to 9 of the accompanying drawings, there is provided a machine frame 9 and a cam shaft 10 mounted in the machine frame, the latter carrying the 30 cams enabling the machine to carry out its different mechanical functions.

In the machine frame is located the mould disc 11 wherein are mounted the moulds 12. The mould disc is rotatably mounted on the mould slide 12a adapted to slide on the machine frame in a transverse direction. The mould slide is 35 operated by a cam mounted on the cam shaft 10. In the mould wheel slide and likewise slid- 40 able in a transverse direction is also mounted the ejector slide 13 which is connected to the ejector slide lever 15 by means of a link 14, the said lever being pivotally mounted about the pivot 16 on the machine frame. The ejector blade is moved forward towards the mould in the 45 customary manner, a nose piece 17 being provided on one arm 15 of the ejector lever, the said nose piece being adapted to come into contact periodically with a nose piece 18 on a cam disc 19 and to be taken with it. In order to return 50 the ejector lever 15 from its forward into its initial position a roller 20 is used, adapted to engage with the edge 21 of a drum-like ring 22 rotatable with the shaft 10. This drum-like ring 22 is cut away over a section in order to offer to 55

the roller 20 a clear passage for the forward movement of the ejector.

A depression 23 also formed in the ring 22 is adapted to receive the roller 20 when it runs on the ring. This causes the ejector lever 15 to perform a short swinging movement resulting in a forward movement of the ejector slide.

In the mould wheel slide 12a are located next to each other a large number of narrow strips or blades 24 constituting the ejector. The respective blades are connected to rods 25 which are guided in grooves of the mould wheel slide. In the rear of each of these rods 25 there is provided in the slide 12a a spring 26. The springs are located in recesses of the slide 12a which prevent their spreading beyond certain limits. They are supported at one end against the end wall of the pertinent recess and at the other end against the ends of the pertinent rods 25 pressing the latter and the blades 24 connected to the said rods towards the mould.

A transverse ledge or step 27 is provided on the ejector slide 13 and in reference to the latter is movable perpendicularly to the direction of movement of the slide, carrying for this purpose two studs 28 (Figure 9) arranged to project into a casing 29 affixed to the slide 13, e. g., by means of screws. In the said casing, springs 30 are located which, on one side rest against a collar 30 of the stud 28, and on the other side against the end of the casing 29, and thereby press the transverse step 27 against the slide 13. A stud 31 fitted with a knob is arranged on the ledge 27 between the two guiding studs 28.

On the machine frame is mounted a double lever pivotal about a stud 32, which at its end 33 is forked, while its other end carries a roller 34 adapted to come into contact with a cam 35 on the ring-shaped cam disc 22. By means of a spring 36 the said lever is held in the position in which the forked portion 33 rests against the slide 13. The studs 31 are so positioned in reference to the lever that they will engage the fork 33 when the slide is retracted.

The mode of operation of the mechanism described is as follows:

In their initial position the parts occupy the positions shewn in Figures 1 and 4. The nose pieces 37 provided on the individual rods 25 are located in the rear of the ledge 38 of the rail 27, and consequently all the rods 25 are held against forward movement towards the mould.

When the operative cycle begins, the cam shaft 10 with the cams thereon, rotates in the direction of the arrow. Shortly after the commencement of the operative cycle, the roller 20 drops into the recess 23 of the ring 22, and consequently the ejector slide 13 performs a small forward movement towards the mould. Almost simultaneously the roller 34 comes into contact with the cam 35 and so rocks the lever 33 that the latter moves the stud 28 from the position in which it is shown in Figure 4 into the position according to Figure 5. The result of this is that the nose pieces 37 are brought out of engagement with the ledge 38, and the rods 25 become free, so as to be enabled through the action of their springs 26 preliminarily to advance until the nose pieces 37 bear against a ledge 39 of the ejector slide 13. Those rods 25 which are connected to the ejector blades located in the rear of the liners of the mould in operative position, cannot take part in the said movement, as the ejector slide has been moved forward to such an extent, that the forward ends of these blades are in contact with the

mould, and the nose pieces of the said rods thus remain in the rear of the ledge 38. The remaining blades located opposite the mould slot are capable of penetrating into the mould so that the nose pieces 37 of the pertinent rods 25 slide over the ledge 38 of the rail 27, until they come up against the ledge 39 of the ejector slide 13. When, during the further movement of the cam shaft, the lever 33 again becomes free and the rail 27 under the action of the springs 30 again returns into the initial position, the nose pieces 37 of those rods 25, of which the ejector blades have passed into the mould slot, are located between the ledge 38 of the rail 27 and the ledge 39 on the slide 13. The parts now occupy the positions in which they are shown in Figure 2 and in section in Figure 5 or 6.

During the continued operation of the machine, the roller 20 is forced out of the recess 23 and the ejector lever 15 is moved back into its initial position. Consequently the ejector slide 13 is also moved back and thereby takes with it the ejector blades 24. The said parts thus resume the position shown in Figure 1, except that some of the ejector blades are slightly in front of the others. The nose pieces 37 appertaining to the projecting blades are located in the rear of the ledge 39; the nose-pieces of the other blades on the other hand, are located in the rear of the ledge 38. During the greater part of the remaining operative cycle, the parts remain in the said position until towards the end of the operative cycle the abutment 18 comes into contact with the abutment 17 on the ejector lever and allows the actual ejecting operation to proceed. Those ejector blades of which the nose pieces 37 are located between the two ledges 38 and 39 then forcibly partake in the said movement. They penetrate into the mould slot and eject the slug located therein. On the other hand, the remaining ejector blades merely move forward through the action of the springs 26 until a further spread of the springs is no longer possible, the blades hardly coming into contact with the mould, or with the liners of the mould; in every such case, however, the springs 26 are able to yield and the blades caused to recede. During ejection the position of the respective parts is that shown in Figure 3 and in the sections according to Figures 7 and 8, Figure 7 showing the position of the inoperative ejector blades and Figure 8 the position of the blades which have been guided through the mould.

After the ejecting operation, the ejector lever is again moved back in the usual manner by the edge 21 of the cam ring 22 and the parts return into their initial positions except that now some of the nose pieces 37 of the respective rods 25 are partly in front, and some are partly in the rear of the ledges 33.

If, during a subsequent operative cycle, another mould is brought into adjustment in the mould disc, the ejector is immediately changed automatically in the manner previously described because shortly before the commencement of each operative cycle all the blades are released and only those capable of penetrating into the mould slot are coupled to the slide to become active at the next operative cycle.

In a modified form of the invention shown in Figures 10 to 12, the mechanism is arranged so that the ejector blades are not advanced to the mould slot and set in relation to the ejector slide according to the dimensions of the slot, during each operative cycle of the machine, but

only during the operative cycle succeeding the interchange of the mould wheel by adjustment of the mould wheel or otherwise (e. g., by opening the vise frame and exchanging the mould which is in operative position.)

In this construction of the invention the ejecting mechanism is of identical construction to that described above. The coupling of the blades of the ejector to the ejector slide is also effected here by the coupling rail 27, which, by means of the stud 31, engages the forked extremity 33 of the lever swinging about the pivot 32. The said lever carries at its other end the roller 34 adapted to co-operate with the cam piece 35 on the cam disc 22 and thereby effect the uncoupling or as the case may be the coupling in the manner described.

The roller 34 is mounted on a stud 40 which is capable of sliding in a bore 41 of the lever 33. The said stud has two notches 42 in which is adapted to penetrate a flat spring 43 so as to lock the stud and the roller 34 in both end positions. A spring 44 which is attached at one end to a stationary part of the machine and at the other end to the stud 40, tends to pull the stud out of the forward position shewn in Figure 12 into the rearward position. On its underside the stud 40 is provided with a pin 45 running in a slot of the lever 33. Against this pin 45 rests a lever 47 mounted on the machine frame, and capable of swinging about a stud 46. To the lever 47 is attached a link 48, the other end of which is connected to the arm 49 of a double lever pivotally mounted about the stud 50. The second arm 51 of this double lever is so bent that its end lies in front of the pinion 52, which, as is known, is axially displaceable on the machine frame, and is employed for rotating the mould disc 11. When the pinion is in its slid-in position, it is coupled to the driving mechanism of the machine, and rotates the mould disc, as known, either to the extent of one-quarter turn, or three-quarters of one turn. If, on the other hand, the mould has to be changed, the pinion 52 is pulled forward in the direction of the arrow, by means of the handle 53, so as to disconnect it from the driving mechanism of the machine, but it still remains in mesh with the mould disc 11, and by turning the pinion 52, the mould disc 50 can be rotated until the desired mould reaches the operative position.

On the cam 22, a further cam piece 54 is arranged which, with its inner surface is capable of acting on the roller 34 or on its stud, and thereby move the roller axially.

The mode of operation of the means described is as follows:

When the roller 34 is in the advanced position shewn in Figures 10 and 12, it will operate in the manner described in connection with the device shewn in Figures 1 to 9, and effect the uncoupling of the ejector blades by means of the ejector slide. As soon as an uncoupling operation has taken place, however, and complementary thereto, the further rotation of the cam disc 22 causes the cam piece 54 to become active. It pushes the roller 34 with its stud, axially into the bore 41, until it is locked in the slid-in position by the spring 43. The uncoupling of the ejector 70 takes place in the manner indicated previously, but at each subsequent operative cycle the ejector blade coupling is no longer released, because the roller 34 now lies beyond the reach of the cam piece 35 and in consequence of this, the uncoupling of the ejector blades need no longer be at-

tempted. The ejector thus remains invariably set until a change of mould has to be made. If, for this purpose, the handle 53 with the pinion 52, are pulled forward in the direction of the arrow, the lever 49-51, is rocked about its pivotal stud 50 as the extremity of the lever 51 rests against the pinion 52. Consequently, the lever arm 49 moves the link 48 and therewith the lever 47 in the direction of the arrow. The head of the lever 47 thus presses against the pin 45 and shifts the stud 40 with the roller 34, back into the position shewn in Figure 12, in which it is again located in the operative position, so that at the next operative cycle, the ejector blades are again uncoupled and a fresh adjustment takes place in 15 the manner described.

An alteration in the size of the mould slot or a change of moulds can also be effected without rotating the mould disc, if, by tilting forward the vise frame of the machine in order to allow 20 access to the mould disc, the mould in operative position is unscrewed, and replaced by a new one, or the liners merely exchanged. In order to ensure that in such case the uncoupling of the ejector blades takes place for the purpose of effecting 25 the fresh adjustment referred to previously, a sliding block 55 is provided, located in the machine frame, and is so operatively connected to the vise frame, that when the vise frame is tilted back, it is moved rearwardly, that is towards the 30 left in Figure 10. A manner in which this can be effected, is, for instance, by the insertion of a stud in the sliding member 55, the said stud being connected to a double lever, the free arm of which rests in front of the vise frame. At the 35 rear end of the sliding member 55 is mounted a resilient bolt 56 resting against the lever 47. When the vise frame is tilted forwards the sliding member 55 through the bolt 56 presses the lever 47 into the position in which it is shewn in Figure 10, so as to bring the roller 34 in the operative position in the manner hereinbefore mentioned. The bolt 56 is resiliently mounted so as to enable the spring eventually to take up the 40 excess motion of the sliding member 55, but the 45 said spring must be powerful enough to overcome the resistance when the roller 34 is shifted.

It may naturally happen that it is necessary to open the vise frame for other purposes, and when the mould does not actually require any alteration. In such cases, the roller 34 is also brought into the operative position and as a complementary function, a single uncoupling of the ejector blades takes place. This, however, is of no consequence, as the vise frame is comparatively seldom opened, and as a general rule, the uncoupling 50 will be avoided. Any convenient alternative means may be used for causing the vise frame to act upon the roller 34 when it is opened or when the pinion 52 is pulled forward, and the sliding 60 of the roller 34 into the operative position may be effected during the changing of a mould by the movements performed by any other machine part.

It should be understood that the invention is not restricted solely to the details of the form 65 described above, since various modifications may be introduced as they become desirable in order to carry the invention into effect under different conditions and requirements which have to be fulfilled, without departing from the scope of 70 the invention.

Having described our invention, we declare that what we claim and desire to secure by Letters Patent is:

1. Slug ejector mechanism for a typographical 75

- slug casting machine comprising a sectional ejector blade adjustable in width, and means actuated by a periodically power actuated part of the machine and controlled by cooperation with the casting slot of the mould in use for automatically adjusting the effective width of the blade in accordance with the length of said mould slot.
2. Slug ejector mechanism for a typographical slug casting machine comprising an ejector slide, a plurality of blade sections slidably mounted therein, means for holding selected sections in and out of slug ejecting positions, and automatic means, actuated by a periodically power actuated part of the machine and controlled by cooperation with the casting slot of the mould in use, for selecting the number of sections appropriate to eject a slug from said mould slot, and for adjusting said selected sections to their operative positions.
- 20 3. Slug ejector mechanism for a typographical slug casting machine comprising an ejector slide, a plurality of ejector blade sections slidably mounted therein, means for moving said slide towards the mould prior to a casting, means controlled by a periodically power actuated part of the machine for automatically adjusting some of said sections to project into the mould slot during the pre-casting time during which the slide is against the mould, means for thereafter locking the sections in position relatively to the slide, and means for withdrawing the slide to its normal inoperative position pending the casting of a slug.
4. Slug ejector mechanism for a typographical slug casting machine according to claim 3 wherein said sections are urged towards their operative positions in the slide by spring means in the slide acting against catches or stops for locating the sections.
- 40 5. Slug ejector mechanism for a typographical slug casting machine according to claim 3 comprising catch means for holding said sections in operative or inoperative positions in relation to said slide, and means controlled by a periodically power actuated part of the machine for releasing said catches before the slide is moved against the mould and for re-setting said catches after the said automatic adjustment of said sections in accordance with the mould.
- 50 6. A typographical slug casting machine comprising a slotted mould interchangeable for a mould with a slot of a different size, an ejector slide with an ejector blade formed of sections slidably therein, a power actuated cam wheel for operating said mould and slide, and means ac-
- tuated by said cam wheel and controlled by cooperation with the casting slot of the mould in use for automatically adjusting the number of blade sections in operation according to the size of said mould slot.
7. A typographical slug casting machine according to claim 6 comprising means for bringing together the mould in use and said slide, prior to a casting, spring means in the slide for urging said sections towards the mould, catch means normally locking sections relatively to said slide, means actuated by said cam wheel for releasing said catches when the mould and slide are brought together, and thereby allowing entry into the mould slot of those blade sections which are embraced thereby, means for re-locking the blade sections in their new positions in the slide, and means for thereafter withdrawing the slide to its normal position, pending a casting.
- 20 8. Slug ejector mechanism for a typographical slug casting machine with an interchangeable mould comprising a sectional ejector blade adjustable in width, and means operated by a periodically actuated part of the machine only after the mould has been changed for automatically adjusting the effective width of the blade in accordance with the length of the newly provided mould slot.
9. Slug ejector mechanism for a typographical slug casting machine with an interchangeable mould comprising a sectional ejector blade adjustable in width, and means for automatically adjusting the effective width of said blade according to the length of mould slot in use, said means being normally in an inoperative position but being moved into a position for operation by a periodically actuated part of the machine, by an element of the machine which is moved only for the purpose of changing the mould.
- 20 10. Slug ejecting mechanism according to claim 9 wherein said means are moved into operative position by manually operated means.
11. Slug ejecting mechanism according to claim 9 wherein said means are automatically returned to their normal, inoperative position after a single operation from said periodically actuated part of the machine.
12. Slug ejecting mechanism according to claim 10 comprising an extensible lever member connected by a linkage to the mould wheel pinion, and adapted to be extended by said linkage into the path of an operating cam when said pinion is withdrawn for disconnection from its drive.
